(57) **CLAIM**

The ornamental design for a flowmeter, as shown and described.

DESCRIPTION

FIG. 1 is a front elevation view of a flowmeter.

FIG. 2 is a rear elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a cross-sectional view thereof taken along line 7—7 in FIG. 2.

FIG. 8 is a cross-sectional view thereof taken along line 8—8 in FIG. 4.

FIG. 9 is a cross-sectional view thereof taken along line 9—9 in FIG. 2; and,

FIG. 10 is a referential view showing use.

The broken lines shown in the drawings are for the purpose of showing environmental structure only and form no part of the claimed design.
